UNITED STATES PATENT OFFICE.

WILLIAM M. ANDERSON, OF MINNEAPOLIS, MINNESOTA, ASSIGNOR TO THE HYDRO VENTILATOR COMPANY, OF MINNEAPOLIS, MINNESOTA, A COMMON LAW COMPANY OF MINNESOTA.

VENTILATED WATER-CLOSET BOWL.

1,266,534.

Specification of Letters Patent. Patented June 4, 1918.

Application filed September 1, 1917. Serial No. 189,253.

To all whom it may concern:

Be it known that I, WILLIAM M. ANDERSON, a citizen of the United States, residing at Minneapolis, in the county of Hennepin and State of Minnesota, have invented certain new and useful Improvements in Ventilated Water-Closet Bowls; and I do hereby declare the following to be a full, clear, and exact description of the invention, such as will enable others skilled in the art to which it appertains to make and use the same.

My invention relates to ventilated water closet bowls and has for its object to provide means for producing a forced draft in the ventilating stack to which said bowl is attached.

To the above end, the invention consists of the novel devices and combinations of devices hereinafter described and defined in the claims.

In the accompanying drawings, which illustrate the invention, like characters indicate like parts throughout the several views.

Referring to the drawings, Figure 1 is a view, partly in side elevation and partly in vertical section, and illustrating a building and water closet in which the invention is incorporated;

Fig. 2 is a fragmentary detail view, on an enlarged scale, with some parts shown in different positions by means of broken lines;

Fig. 3 is a detail view, principally in plan, with some parts sectioned on the irregular line 3—3 of Fig. 2; and

Fig. 4 is a view, principally in vertical section, taken on the line 4—4 of Fig. 3, on an enlarged scale.

Of the parts of the building illustrated, the numerals 5 and 6 indicate, respectively, the floor of a bath or other room and a partition separating this room from an adjacent room. To the floor 5, is secured a closet bowl 7, of the siphon action, wash down type, and to the wall 6, is secured a low water tank 8 that is connected to the closet bowl 7 by a connection disclosed and broadly claimed in my co-pending application, Serial Number 155,645, filed March 19, 1917, and entitled "Ventilated water closet bowls."

This connection comprises a flushing elbow 9, having an extension 10 that is axially aligned with the delivery end thereof and connected to a ventilating stack 11 by an elbow 12. The stack 11 is located between

the walls of the partition 6 and, as shown, 55 the extension 10 is rigidly secured to the elbow 9 by solder and rivets, and said elbow is cut away to afford a communicating passageway therebetween.

In the rim of the bowl 7, is the customary 60 flushing passageway 13 and annular passageway 14, the former of which affords direct communication between the elbow 9 and bowl 7, and the latter of which has communication with said bowl through a multiplicity of circumferentially spaced holes 15. Anchored to the bowl 7, is a pair of hinge posts 16 in which is journaled a horizontal rock shaft 17, having rigidly secured thereto, at their intermediate portions, a 70 pair of horizontal levers 18. These levers 18 are located inside of the hinge posts 16 and engage the same to hold the rock shaft against endwise movement.

The short ends of the levers 18 project 75 forward and have the hinge members 19 of a seat 20 connected thereto by hinge pins 21, and the hinge members 22 of a seat cover 23 are connected to the long arms of said lever by hinge pins 24. The weight of the cover 80 23, whether open or closed, acting on the long arms of the levers 18, will normally hold the rear end of the seat 20 slightly raised, while the front end thereof is supported on the rim of the bowl 7. 85

Interposed in the flushing elbow 9, above the extension 10, is a horizontal cylindrical valve casing 25, which projects radially therethrough from the front to the rear. Integrally formed with this valve casing 25, 90 are upper and lower annular flanges 26, into which the adjacent ends of the sections of the elbow 9 are telescoped and rigidly secured by solder to form water-tight joints therebetween. Water is supplied to the tank 8 through a pipe 27 leading from a suitable source under pressure, and a branch water pipe 28 connects the said pipe 27 with the rear end of the valve casing 25. Within the valve casing 25, is a partition 29, having 95 an axial port 30, which affords communication between the receiving end of the chamber in said valve casing and the delivery end thereof. This port 30 is normally closed by a ball valve 31 arranged to close with the 100 water pressure.

Leading from the delivery end of the valve casing 25, is a tube 32, having on its

outer end a spraying nozzle 33. The tube 32 extends from the valve casing 25, through the flushing elbow 9 toward the bowl 7, and just before it enters said bowl, the same 5 is bent upon itself, so that the nozzle 33 projects rearwardly in axial alinement with the extension 10.

When the seat 20 is depressed, the ball valve 31 is forced from its seat to open the port 10 30, by a long stem 34 which works through a stuffing box 35 on the front end of the valve casing 25. Endwise movement is imparted to the stem 34 by an eccentric 36, secured to the shaft 17, and a link 37, connected at 15 one end to said eccentric by an eccentric strap 38 and having its other end pivotally connected to the outer end of the stem 34. The eccentric is so positioned on its shaft 17, that it normally holds the stem 34 slightly 20 out of contact with the ball valve 31, so that the same may be held seated by the water pressure. At the time the seat 20 is depressed, the stem 34 is moved rearward by the eccentric 36, engages the ball valve 31 25 and forces the same from its seat against the water pressure.

With the ball valve 31 open, water from the branch pipe 28 will be admitted through the port 30 to the tube 32 and sprayed by 30 the nozzle 33 into the elbow 9 and extension 10, as indicated in Fig. 2. This water spray will create a suction in the bowl 7 and produce a forced draft in the stack 11 through the openings 15, passageway 14, elbow 9, 35 and extension 10. After the water spray has spent its force, the same will drain into the bowl through the extension 10, elbow 9 and flushing passageway 13. When the pressure is removed from the seat 20, the water spray 40 is automatically cut off by the weight of the cover 23, acting on the levers 18 to raise the rear end of the seat 20 and turn the shaft 17 to operate the eccentric 36, and thereby move the stem 34 out of contact with its 45 ball valve 31 to permit the same to be closed by the water pressure.

From the above description, it is evident

that the action of the invention is entirely automatic and simple, with few parts to get out of order. It is also evident that the 50 device may be manufactured at a comparatively small cost and easily installed and, in actual usage, the same has proven highly efficient for the purpose had in view.

What I claim is:—

1. The combination with a closet bowl, a water supply, a ventilating stack and a single connection between the closet bowl, water supply and ventilating stack, of a spraying nozzle connected to the water supply, located 60 in said connection and arranged to direct a spray of water toward the ventilating stack.

2. The combination with a closet bowl, a water supply, a ventilating stack and a single connection between the closet bowl, water 65 supply and ventilating stack, of a water pipe leading from the water supply and having a spraying nozzle located in said connection and arranged to direct a spray of water toward the ventilating stack, a valve interposed in the water pipe and incorporated in 70 said connection, and means for opening and closing the valve.

3. The combination with a closet bowl, a water tank, a water supply pipe leading to the 75 water tank, a ventilating stack, and a flushing bend connecting the water tank and closet bowl, said bend having an extension connecting the delivery end thereof with the ventilating stack, of a valve casing interposed in the flushing bend at its receiving end and connected to the water supply pipe, a normally closed valve in said casing, a water tube leading from the valve casing and having a spraying nozzle located in the delivery end of the flushing bend, and means 80 for opening said valve.

In testimony whereof I affix my signature in presence of two witnesses.

WILLIAM M. ANDERSON.
